DESIGN FOR A BOTTLE

Edwin W. Fuerst, Toledo, Ohio, and John W. McPherrin, Evanston, Ill., assignors to The Kendall Company, Boston, Mass., a corporation of Massachusetts

Application April 19, 1934, Serial No. 51,463

Term of patent 14 years

To all whom it may concern:

Be it known that we, EDWIN W. FUERST, a citizen of the United States, residing at Toledo, in the county of Lucas and State of Ohio, and JOHN W. MCPHERRIN, a citizen of the United States, residing at Evanston, in the county of Cook and State of Illinois, have invented a new, original, and ornamental Design for a Bottle, of which the following is a specification, reference being had to the accompanying drawing forming a part thereof.

In the drawing:

Fig. 1 is a front elevational view of a bottle showing our design.

Fig. 2 is an end elevational view thereof.

Fig. 3 is a top plan view.

We claim:

The ornamental design for a bottle substantially as shown.

Signed by said EDWIN W. FUERST, at Toledo, in the county of Lucas and State of Ohio, this 13th day of April, 1934.

EDWIN W. FUERST.

Signed by said JOHN W. MCPHERRIN, at Evanston, in the county of Cook, and State of Illinois, this 16th day of April, 1934.

JOHN W. MCPHERRIN.
